CLAIM

The ornamental design for a vehicular weapon mount, as shown and described.

DESCRIPTION

FIG. 1 is a top left perspective view of the vehicular weapon mount of the instant invention;

FIG. 2 is a rear view thereof;

FIG. 3 is a front view thereof;

FIG. 4 is a top view thereof;

FIG. 5 is a bottom view thereof;

FIG. 6 is a left side view thereof;

FIG. 7 is a right side view thereof;

FIG. 8 is a left perspective view thereof illustrating the device in combination with a weapon; and,

FIG. 9 is a top perspective view illustrating the device secured within a motorcycle saddlebag.

The portions of the figures illustrated in broken lines are for illustrative purposes only and form no part of the claimed design.
